BOWLING BALL RETARDER

William F. Huck, Forest Hills, N. Y., assignor to
 The Brunswick-Balke-Collender Company, a
 corporation of Delaware

Application April 5, 1951, Serial No. 219,458

5 Claims. (Cl. 273—47)

1

This invention relates to a bowling ball retarder or stop device and particularly to a bowling ball retarder having sufficient capacity to stop or retard two bowling balls which strike the device in quick succession.

In bowling, after a player makes a shot, a pin boy, or in some cases an automatic ball returning machine, places the ball upon a return track located alongside the alley and sufficient momentum is imparted to the ball to enable it to return to a rack located at the player's end of the alley. The rack comprises a pair of parallel rails which will hold bowling balls. Each end of the rack is supported, the end support nearest the player being a terminal unit which has a ball stop surface to arrest the movement of balls coming onto the rack. The rack is lined up at its alley end with a return track so that a ball which is returned along the return track will automatically pass upwardly over a rising portion of the track and then enter the rack.

In order to avoid damage from returning balls, a ball retarder is used at the entrance end of the ball rack. These retarders are generally designed to stop the progress of a ball and then permit it to roll by gravity down a slight decline in the rack rails to the storage portion and thereby enable all balls to enter the rack at a uniformly slow speed.

The present invention discloses a tandem arrangement of ball retarders which will take care of two balls returned in rapid succession. Accordingly an object of this invention is to provide a new and improved ball retarder for use in a bowling alley whereby balls being returned at a relatively high speed will have their speed decreased to a safe level upon entering the ball rack.

Another object of the invention is the provision of a plurality of ball retarders to prevent each of a number of bowling balls being returned in quick succession from passing onto the ball rack at an excessive speed.

A further object of the invention is to provide a ball retarder having a pair of closely spaced ball retarding devices capable of handling balls returned in quick succession.

A still further object of the invention is to provide a ball retarder in which the operation of one of a plurality of retarding devices enables another retarding device to become operative.

Still another object of the invention is to provide a plurality of ball retarders having interconnected dashpots whereby the retarder units are made operative in sequence, the operation of one retarder enabling the dashpot in another re-

2

tarder to offer resistance to the passage of a following ball engaging the other retarder.

Other objects and advantages will be apparent from the description and drawing, in which:

5 Fig. 1 is a side elevation, partially in section, of the improved bowling ball retarder showing particularly the linkage between the two retarders;

10 Fig. 2 is a front view of the device of this invention showing the blocking means of the retarder element; and,

15 Fig. 3 is an enlarged sectional view showing the valve arrangement of one of the dashpot pistons.

20 While this invention is susceptible of embodiment in many different forms, there is shown in the drawing and will herein be described in detail one specific embodiment, with the understanding that the present disclosure is to be considered as an exemplification of the principles of the invention and is not intended to limit the invention to the embodiment illustrated. The scope of the invention will be pointed out in the appended claims.

25 Referring now to the drawings, the device of this invention is adapted to be used in conjunction with a bowling ball return track supported in elevated position above the floor 2 of the alley. The return track includes cross braces 3 and 4 which support a trackway member 5 through the 30 medium of the base support 6. Mounted on the trackway are a pair of rails 7 (Fig. 2) along which bowling balls 8 and 8' are adapted to roll.

35 The retarding device is located within a closure having side panels 9 and 9a which extend from the floor to a position above the track 7, the general shape of the side members 9 and 9a being indicated in broken lines in Fig. 1. Within the closure defined by the side walls are located two dashpots generally indicated 10 and 11 which 40 form a part of the retarding device of the invention. Inasmuch as many of the component parts of the retarding devices including the dashpots 10 and 11 are similar, similar parts have been given identical reference numerals with those associated with the dashpot 10 being primed in order to simplify the disclosure.

45 Thus, each dashpot includes a U-shaped ball blocking member having a pair of arcuately curved arms 12 and 12a pivoted intermediate their ends to stud shafts 13 and 13a respectively fixed in the side supports 9 and 9a. The arms are connected by the base member 14 of the U-shaped ball blocking member which is provided with a pair of spaced crank arms 15, 15a which 55 rotatably supports a bearing pin 16 to which the

upper end of piston rod 18 is connected. Rollers 19 and 19a are provided at the outer ends of each of the arms 12 and 12a and are preferably constructed of rubber or other resilient material. These rollers extend in blocking relationship into the path of movement of a ball rolling along the trackway.

The dashpot devices 10 and 11 each include a cylinder 21 pivotally mounted at its lower end upon a bracket 23 fixed to the floor and each is provided with a piston 24 reciprocable therein and secured to the piston rod 18. Each piston is provided with a longitudinally extending passage adapted to be partially blocked by a check valve 25 in order that the piston and cylinder devices may function as dashpots in the well known manner.

The portion 20 of the cylinder below the piston forms a reservoir for the fluid used in operating the dashpots. Preferably this fluid is a hydraulic fluid, such as oil, although clearly other fluids may be used. A compression spring 26 is located in the reservoir 20 and bears against the lower end of the cylinder and the lower end of the piston constantly to urge the piston toward the position illustrated in Fig. 1 in which the retarders are positioned in blocking relationship to a ball moving along the track.

It will be noted that the upper and lower ends of the cylinder 21 are connected together by fluid passages including the conduits 27 and 28. The conduit 28 is connected to a port 29 in the lower end of the reservoir 20 and to a port 31 in the upper end of the reservoir 20' and immediately below the piston 24' therein. A second port 32 positioned opposite the port 31 is connected to one end of the conduit 27, the other end being connected to the port 33 in that part of the cylinder 21 above the piston 24.

Referring to Fig. 3, it will be noted that the piston 24 is provided with a passage 34 extending longitudinally therethrough in which passage there is located a rod 35 connected at one end to the ball check valve 25 and at the other end extending up into the hollow in the piston rod 18. A plurality of fluid passages 36 connect the portion 37 of the cylinder above the piston with the passage 34 so that oil may pass through the piston to permit damped movement thereof.

The operation of the device is believed to be obvious from the foregoing description. When a first ball 8' rolls along the trackway it first strikes the right-hand retarder. Inasmuch as the piston 24' is at that time in the position illustrated in Fig. 1, the piston 24 may move freely downwardly within the cylinder 21 because of the fluid passages provided connecting the two ends of the cylinder 21 together. Thus the right-hand retarder is inoperative to block a ball and is pivoted freely by the ball to the position shown in broken lines in Fig. 1. The ball continues until it strikes the left-hand retarder which effectively blocks the ball in its passage along the track. The weight of the ball moves the left-hand retarder down to the position shown in broken lines in Fig. 1, whereupon the ball 8' will be released. The downward movement of the left-hand retarder moves the piston 24' downwardly within the cylinder 21'. If during the time that the piston 24' is moving downwardly in response to the weight of the ball 8', a second ball 8 should roll along the trackway it will be blocked by the right-hand retarder inasmuch as the ports 31 and 32 would then be blocked by the elongated piston 24'. When this condition pre-

vails, the right-hand dashpot is rendered operative to block a ball and then to release it when the piston is moved downwardly to lower the arms to the position shown in broken lines.

5 Clearly, if the arrangement of the alley is such that more than two balls may roll at one time along the trackway, a third retarding device constructed similarly to the device 11 may be included in the retarding system. The third retarder would include a cylinder having its ends connected together by passages and ports similar to the passages and ports 27-33 although they would be connected to the cylinder 21 rather than to the cylinder 21'. Additional units similarly 10 linked in tandem may be provided should the occasion require.

I claim:

1. In a bowling ball return device having a fixed runway for the balls a retarding device comprising at least a first and second retarder pivoted on said runway and normally positioned in the path of a ball on the runway for retarding the movement of the ball and later releasing it, a damping element for each retarder, and means including a control connection between damping elements operative to cause either a reduction in the damping effect on the first retarder when the second retarder is not blocking a ball or to restore said damping effect on said first retarder when said second retarder is blocking a ball.

2. A retarding device for a bowling ball return track comprising, a first retarder, a second retarder, said retarders being separately mounted in spaced apart positions along said track and normally positioned in the path of a ball moving along said track with each of said retarders being adapted to stop a ball and then to release it, means for rendering the first retarder inoperative to block a ball, and means actuated by the second retarder when blocking a ball to render the first retarder operative to block a second ball moving along said track.

3. A bowling ball retarding device for use with a return track comprising, a first and a second retarder spaced apart along said track and normally positioned in the path of a ball moving therealong, means adapting each retarder to stop a ball and then to release it including a hydraulic piston and cylinder device for each retarder, a restricted opening through each piston to form a dashpot, a fluid passage normally connecting together the ends of the cylinder for the first retarder to render the last mentioned retarder inoperative to block a ball, and means operative by movement of the piston associated with the second retarder to close said passage to render the first retarder operative to block a ball.

4. A bowling ball retarding device for use with a return track comprising, a first and a second retarder spaced apart along said track and normally positioned in the path of a ball moving therealong, means adapting each retarder to stop a ball and then to release it including a hydraulic piston and cylinder device for and connected to each of the retarders, an opening through each piston to form a dashpot, resilient means in each cylinder for moving the piston therein to one end of the cylinder to move the retarder connected thereto into the path of a ball moving along the track, a fluid passage connecting together the ends of the cylinder associated with the first retarder, said passage including the portion of the cylinder of the second retarder immediately adjacent the lower edge of the piston therein whereby movement of the last mentioned piston in response to a first ball held in its re-

tarder closes said passage to render the first retarder operative to block a second ball moving along said track.

5. A bowling ball retarding device for use with a return track comprising, a first and a second retarder pivotally mounted in spaced relationship along said track and normally positioned in the path of a ball moving therealong, means adapting each retarder to stop a ball and then to release it including a hydraulic piston and cylinder device for each retarder, a piston rod connecting each piston to its associated retarder, a spring in each cylinder constantly urging the piston therein upwardly to pivot the retarder connected thereto into the path of a ball moving along said track, an opening through each piston to form therewith a dashpot whereby to block a ball moving along said path and later to release it with downward movement of the piston, a fluid passage connecting the portion of the cyl-

inder of the first device below the piston therein to the portion of said cylinder above the piston to render said piston freely movable downwardly, said passage including the portion of the cylinder of the second device immediately beneath the piston in said second device whereby downward movement of the last mentioned piston in response to a first ball held in its associated retarder blocks said passage to render the first retarder operative to block a second ball moving along said track.
